UNITED STATES PATENT OFFICE.

CHARLES BROWN, OF NAPLES, ITALY, ASSIGNOR TO GUSTAV JACOB MELMS, OF CHICAGO, ILLINOIS.

STEAM-ENGINE.

SPECIFICATION forming part of Letters Patent No. 437,353, dated September 30, 1890.

Application filed April 11, 1890. Serial No. 347,434. (No model.)

To all whom it may concern:

Be it known that I, CHARLES BROWN, a resident of Naples, Italy, have invented certain new and useful Improvements in Steam-Engines; and I do hereby declare that the following is a full, clear, and exact description thereof, reference being had to the accompanying drawings, and to the letters of reference marked thereon, which form a part of this specification.

This invention relates to improvements in steam-engines, and more particularly to improvements in valves for such engines, and in features of construction in compound steam- engines.

The invention consists in the matters hereinafter described, and pointed out in the appended claims.

In the accompanying drawings, illustrating my invention, Figure 1 is a central axial section through the end of the steam-cylinder of an engine, illustrating the cylinder-ports and a valve for controlling the same constructed in accordance with my invention. Fig. 2 is a sectional view of the valve shown in Fig. 1, taken in a plane at right angles to the axis of the cylinder in the line 2 2 of Fig. 1. Fig. 3 is a partial section, taken upon line 3 3 of Fig. 1, showing the cylinder-ports in side view. Fig. 4 is a detail section, taken upon line 4 4 of Fig. 1, showing one of the valve-springs in side view. Fig. 5 is a central vertical section of a single-acting compound engine embodying my invention, the section being taken on a plane at right angles to the crank-shaft of the engine. Fig. 6 is a sectional view of the said engine on the line 6 6 of Fig. 5, a section being taken on a plane passing through the axis of the crank-shaft. Fig. 7 is a detail section of the engine-valve, taken upon line 7 7 of Fig. 5. Fig. 8 is a section taken through the low-pressure cylinder of the engine upon line 8 8 of Fig. 6. Fig. 9 is a diagram illustrating the part of the revolution of the crank-shaft during which the valve shown in Fig. 8 is open.

A indicates an engine-cylinder, and A' one of the end walls or heads thereof, which is provided at its margin with an annular valve-seat A², in which are formed ports a a, com-

municating with the interior of the cylinder through the head A'.

B is an annular valve plate or ring, which constitutes the main operative part of the valve, and fits and turns upon the valve-seat A².

A³ is an outer or auxiliary head, arranged external to the head A' and forming with the same a live-steam space or passage C, with which communicates a steam-supply passage, (indicated by dotted lines at A⁴, Figs. 1 and 2.) In the particular construction shown in the drawings the head A³ is cast integral with the cylinder-head and connected therewith by webs a⁵ a⁶.

D is a steam-exhaust passage, of annular form, surrounding the valve-ring B, said passage being formed by an external wall A⁵, herein shown as cast integral with the head A'.

An annular slot or opening between the margins of the external head A⁵ and the external wall A⁶ of the exhaust-passage m is closed by an annular plate or cover E, located opposite the valve-ring B. Said slot or opening is made of proper size to admit the said valve-ring, and the latter may be taken out through the said slot by the removal of said cover E. The steam-inlet passage A⁴ is herein shown as extending through the exhaust-passage D and between the valve-seat and the head A' in one of the spaces between two of the ports a a, Fig. 2.

The valve-ring B is provided with a series of recesses or notches b b, opening both at the inner edge and inner flat face of the valve and arranged to correspond in number and angular positions with the ports a a of the valve-seat A². The said recesses b b communicate at the inner edge of the ring with the steam-space C, and serve to admit steam to the said ports when opposite the same. In the instance illustrated the valve-ring is provided with eight of such notches b b. At points intermediate to the notches b b the valve-ring is provided with a second series of notches b' b', which open at the outer edge and inner flat face of the ring and serve to bring the ports a a into communication with the exhaust-passage D.

F is a packing-ring, which is inserted between the valve-ring B and cover E for making a steam-tight joint between the live-steam and exhaust passages or chambers. Said ring F revolves with the valve-ring and fits steam-tight against the main surface of the said cover. A steam-tight joint is formed between the valve-ring and packing-ring by means of an annular packing-strip e', which bears 5 against the inner cylindric faces of the valve-ring and an inwardly-extending flange e of the packing-ring, which flange fits within an annular recess or rabbet b² in the inner face of the valve-ring. The outer cylindric face 10 of said packing-ring and the flange thereon is in contact with the cylindric surface of the rabbet b², but the edge of said flange stands normally free from the opposing surface of the valve-ring when the valve-ring rests on 15 its seat and the packing-ring is in contact with the cover E, said ring being held or supported in contact with the cover by means of a plurality of springs f f, which are interposed between the packing-ring and valve-ring, and act expansively to throw said rings 20 apart. The springs f f are herein shown as made of metal strips bent to engage at their middle parts and ends with the parts between which they are placed, as shown in Fig. 4. 25 By the construction described not only are the valve-ring and packing-ring held at all times in contact with their seats, notwithstanding wear in the parts, which is taken up by the springs f f, but the valve-ring, being movable outwardly by reason of its sliding connection with the packing-ring, is free 30 to rise from its seat when water is present within the cylinder, to permit the escape of the same without danger of breaking the cylinder-head. The packing-ring F bears against 35 the cover E at the inner portion only of its outer surface, and it follows from this construction and the shape of said ring, as above described, that the steam-pressure on said ring is balanced, except in the small area included between the two circles of which the diameters are indicated by the lines 1 and 2 in the drawings. The valve-ring B is made 40 of such cross-sectional shape and the packing-ring is so located with reference thereto that said valve-ring is partially relieved from steam-pressure on its rear or outer surface, inasmuch as the steam-pressure acts only on that area included between the two circles of 45 which the lines 1 and 3, Fig. 1, represent the diameters, and the unbalanced pressure is still further reduced, because it is only active to its full extent on those parts of the eight cylinder-ports a a and the corresponding exhaust-notches b' b' which are located immediately 50 under the pressure-zone included between the circles of which the lines 1 and 3 are the diameters.

The valve-ring B receives motion from the 55 crank-shaft or other moving part of the engine through the medium of a pinion G, which is mounted upon a shaft G' and intermeshes

with a circular rack B', formed on the circumference of the valve-ring. The said pinion G is located within the exhaust passage or chamber D in the manner shown in Figs. 1 and 2, the shaft G' passing through 70 a stuffing-box g, where it makes its exit from the chamber, so as to prevent the escape of steam at this point. As shown in the drawings, the wall A⁵ of the exhaust passage or chamber is divided on a line passing through the bearings of the shaft G', Fig. 2, to form a separate cap or cover A⁶, which may be removed to obtain access to the pinion G. The 75 shaft G', in case the same is driven by the crank-shaft of the engine, may be connected therewith by any suitable gearing, such, for instance, as that shown in Fig. 6 and herein-after described. Said shaft will be so actuated that at each revolution of the crank-shaft the valve-ring B will be turned an angular distance equal to the angular distance apart of the steam-ports in the cylinder—that is to say, in a valve having eight steam-ports, 80 as herein shown, the valve-ring B will make one revolution to eight turns of the crank-shaft.

To now refer to the operation of the valve, Fig. 2 shows the valve-ring in its proper position at the commencement of the stroke, the ports being already partially uncovered for the admission of steam a distance technically known as the "lead"—that is to say, the distance by which the advance edge b³ of the inlet-notch b is separated from the edge a' of the steam-ports. As the piston moves, the valve will continue to revolve until the edges b⁴ of the several notches b coincide with the edges a² of the cylinder-ports, when the admission of steam ceases. The notches b' b' control the periods of exhaust and compression in a similar manner, opening communication of the cylinder with the exhaust by their edges b⁵ b⁵ passing the edges a' a' of the cylinder-ports and closing the exhaust by their edges b⁶ b⁶ passing the edges a² a² of the cylinder-ports. The spacing of the notches b b and b' b' and that of the ports a a is so adjusted as to control the periods of admission and exhaust according to the requirements of theory and practice.

In Figs. 5, 6, 7, and 8 is shown a single-acting compound engine, to the high and low pressure cylinders of which are applied valves 95 of the type above described. As illustrated in said figures, H is the small or high-pressure cylinder, and I the large or low-pressure cylinder, of the engine, said cylinders being arranged end to end and having interposed 100 between them a casting J, which forms the upper head of the cylinder I. Within the cylinder I is a piston i, having a tubular piston-rod i', and the cylinder H contains a piston h', having a piston-rod h², which passes 105 through a central hub J² of the casting J and through the piston i and its tubular piston-rod. Both of said piston-rods are connected 110 with a single crank-shaft Q, as hereinafter

more fully set forth. In the upper surface of said casting J is formed an annular valve-seat J', and within said casting, outside of said valve-seat, is formed an annular exhaust 5 passage or chamber J³. j j j are steam-ports leading from the valve-seat J' into the low-pressure cylinder I. The high-pressure cylinder H is provided at its end adjacent to the cylinder I with an integral head H', upon the 10 outer surface of which is formed an annular valve-seat H², within which is formed a series of ports h h h, leading to the said cylinder.

K is a valve-ring, fitting upon the valve-seat J' and provided with steam inlet and exhaust 15 notches or recesses k k k' k', constructed and operating in all respects like the valve-ring shown in Figs. 1, 2, and 3. A packing-ring L like that shown in Figs. 1, 2, and 3 is also employed, together with a packing-strip l, to 20 make a steam-tight joint between the valve-ring and the packing-ring. The valve-ring K controls the admission of steam to and its exit from the low-pressure cylinder. In this instance, the cylinder H is provided with an 25 outwardly-extending annular flange H³, which is secured at its outer margins to the casting J above the exhaust-chamber J³ and the valve-ring K and forms a cover for said parts, said flange being provided with an annular rib h⁴, 30 forming a bearing-surface for the packing-ring L.

M is a second valve-ring, similar to the valve-ring K, but located within the latter and resting in contact with the annular valve-seat H² 35 of the high-pressure cylinder. Said valve-ring controls the admission of steam to the high-pressure cylinder. N is a packing-ring, located between the said valve-ring M and an annular seat or bearing-surface J⁴, formed 40 upon the casting J, inside of the valve-seat J'. A packing-strip n serves to make a steam-tight joint between the valve-ring M and the packing-ring N.

O is a live-steam chamber, formed in the 45 casting J between the valve-ring N and the head of the low-pressure cylinder, said chamber being of annular form and occupying the space between the cylinder-ports j j and the central hub J² of the casting J. Steam is admitted to said chamber O through a radial steam-inlet passage O'. (Shown in Fig. 6.)

The valve-ring M is supplied on its inner or live-steam circumference with an automatic cut-off valve for controlling the admission 55 period, said valve having the form of a cylinder P, provided with ports p, which operate in connection with the admission openings or notches m of the valve-ring M. Said cylinder P extends from the valve-ring M to the bottom of the steam-chamber O, having bearing 60 against the inner surface of said valve-ring M and against the exterior of the central hub J² of the casting J. An annular space is formed between the exterior of the cylinder P and the bearing-surface J⁴ and packing-ring N, to allow the passage of live steam from the chamber O to the space between the packing-ring

N and the cylinder P, and said cylinder is provided with a series of apertures p', allowing the passage of steam through the cylinder 70 to an annular space or chamber P', formed between the upper part of the said cylinder and the hub J². The steam passes from said space P' through the ports p of the cylinder P into the passage m of the valve-ring 75 M. The cylinder P, constituting the cut-off valve, is held in any angular position desired, so as to cut off the steam at any desired point in the stroke of the piston. Any desired or suitable means may be employed 80 to give motion to the cylinder P from the exterior of the casting J—as, for instance, the said cylinder may be provided with external gear-teeth P², engaged with a rack-bar P³, to which is attached a rod P⁴, extending 85 outwardly through the steam-inlet passage O', or a similar passage provided for the purpose. The rod P⁴ will usually pass through a suitable stuffing-box, and may be connected with any suitable regulating device or governor. 90

The valve-ring M operates in the same manner as the valve-ring B, hereinbefore described, to bring the ports p of the cut-off valve and the exhaust-space alternately into communication with the high-pressure cylinder. Such 95 exhaust-space is included between the valve-rings K and M, and the valve-ring K operates to bring said exhaust-space and the exhaust-passage J³ alternately into communication with the low-pressure cylinder I. The 100 valve-ring K is connected with the valve-ring M by means of interfitting projections m² m³ m⁸, Fig. 7, on said parts, so that the said valve-ring M is moved by and with the said valve-ring K, the latter being actuated by means 105 of a pinion G upon a shaft G' engaging gear-teeth K' on the valve-ring, in the same manner as hereinbefore described. Motion is given to the said shaft G' from the engine crank-shaft Q in the construction shown by 110 means of a pinion R upon the shaft engaging a spur-wheel R' on the shaft r, on which is mounted a gear-pinion R², intermeshing with the gear-pinion G² on the shaft G'.

S is a supplemental valve for controlling 115 the exit of steam from the exhaust-chamber J³ of the low-pressure cylinder. Said valve S has the form of a hollow cylinder secured to and revolving with the shaft, said cylinder being open at its ends and in communication 120 with said exhaust-passage J³. Said valve rotates within a cylindric seat S', located at the side of the cylinder I and in communication at one end with the said chamber J³, said seat having opposite ports S², communicating with 125 the exit steam-passage S³, leading to the open air or to a condenser. Said valve S is provided with ports s s, corresponding in size and location with the ports S² S³ of the valve-seat. The purpose of the valve S is to open communication 130 between the low-pressure cylinder and the condenser or exhaust during such portion of the revolution of the engine as may be necessary to the proper working of the

same. In the diagram Fig. 9 the shaded part of the circle indicates the part of the revolution during which the valve may remain open with good results, the same being about one-third of a complete revolution of the crank-shaft. By making the period during which the low-pressure cylinder is in communication with the exhaust or condenser about one-third of a revolution of the shaft the period during which the cooling and re-evaporating process takes place (which is one cause of the useless expenditure of heat in a steam-engine) is reduced to a minimum.

The engine illustrated embodies as a separate and further improvement means for affording a rapid escape of exhaust-steam from the cylinders, consisting of an annular exhaust-port in each cylinder, which exhaust-port is uncovered by the piston when the latter is at the extreme end of its stroke. In the construction illustrated the high-pressure cylinder H is provided with an annular exhaust-port H⁴, opening into a passage H⁵ in or surrounding the walls of the cylinder, which passage communicates with the space between the valve-rings K and M. The low-pressure cylinder I is provided with a similar annular port I', communicating by means of passages I² I², cast on the wall of the cylinder, with the exhaust-chamber J³. At the side of the cylinder I, adjacent to the valve S, the port I' is desirably arranged to communicate directly with the valve-easing S', as clearly shown in the drawings, Fig. 6.

The supplementary exhaust-ports H⁴ and I' afford a large exhaust-opening as soon as the annular ports with which they are connected are uncovered by the pistons, thereby insuring the rapid and complete discharge of steam and moisture from the cylinders. The passages H⁵ and I² prevent undue compression at the end of the working-stroke of each piston, inasmuch as they form a means of communication between the opposite sides of the piston during the period that the exhaust-ports of the valves K and M are open, thus allowing the steam to circulate freely between the spaces at opposite sides of the pistons at such times.

The valve S constitutes an important improvement in steam-engines, and especially in compound high-speed engines, whereby the latter are better adapted to work either as condensing or non-condensing engines. When the engine is working with condensation, during the upstroke of the piston in the high-pressure cylinder the connection with the condenser and the low-pressure cylinder is cut off. It follows that the pressure of steam on opposite sides of the said piston during such upstroke of the piston is the same as at the completion of the stroke, steam circulating freely both above and below the piston, so that when the valve-ring K cuts off the exhaust a sufficient quantity of steam is confined to produce by compression sufficient end pressure to absorb the momentum of the piston i

of the low-pressure cylinder and parts moving therewith. The cross-head and crank-pin bearings are thus kept constantly in bearing in one direction, and inasmuch as no reversal in the direction of the pressure in said parts takes place a silent motion is secured and pounding is avoided.

As a further and separate improvement, I have provided a novel construction in the piston and connecting rods of a steam engine, as follows: Each of the two separate piston-rods h² i' above described gives an impulse to the crank-shaft during one-half of the revolution of the crank, the impulse of one piston-rod being in an opposite direction to that of the other piston-rod. Any lost motion in the crank or cross-head bearings in a construction of this kind will produce pounding, and to lessen liability thereof I provide the following construction, as more clearly shown in Figs. 5 and 6. The piston-rod i', connected with the piston i of the low-pressure cylinder, which is hollow or tubular for the passage of the piston-rod h², as hereinbefore described, is connected with one half U' of a two-part cross-head, which is indicated as a whole by U. Said piston-rod h² of the high-pressure cylinder is connected with the other part U² of the said cross-head, said parts of the cross-head being movable relatively to each other, while at the same time engaging the cross-head guides T T, so as to properly guide the piston-rods. In the particular construction shown, the part U' of the cross-head is provided at its ends with integral guide-plates u u, which immediately engage the cross-head guides, while the part U² is provided with short bearing-surfaces u' u' on its ends, which rest and slide in contact with the said plates u u.

V V are springs applied to draw the parts of the cross-head toward each other, said springs, as herein shown, being of spiral form and placed between the part U' of the cross-head and nuts or heads v v upon bolts v' v', which bolts pass through the part U' of the cross-head and are secured to the part U² thereof.

The crank-pin bearing is made in two parts or sections W W', the section W covering the part of the bearing nearest the cross-head, while the section W' covers the part of the crank-pin remote therefrom. Said part W of the bearing nearest the cross-head is connected with the latter by means of two connecting rods or bars W² W², which are rigidly secured to said part W of the bearing and engage bearing-pins u² u² on the part U' of the divided cross-head. The lower section W' of the divided bearing is connected with the part U² of the divided cross-head by means of a connecting-rod W³, which is forked at its upper end and provided with a wrist-pin w, passing through the said part U² of the cross-head. The pressure downward of the piston-rod i' keeps the part U' of the cross-head and the connecting-bars W² W² always in com-

pression, there being no reversal in the direction of the force exerted upon the crank-shaft by or through these parts. The piston i of the low-pressure cylinder, therefore, operates under the same conditions as any single-acting engine and can be run without the other half of the crank-pin bearing. The piston-rod h^2 , which passes freely through the hollow rod i' , acts upon the crank-pin through the medium of the lower part U^2 of the cross-head and the connecting-rods W^3 W^3 , and inasmuch as said piston always receives pressure of the steam on its under side the transmitting parts are always in tension and there is no reversal in the direction of force, so that these parts can also work independently of the parts operating on the other half of the crank-pin. It follows that any lost motion in the bearings will not produce pounding, because the steam acts from below in the high-pressure cylinder and from above in the low-pressure cylinder on the pistons and keeps the halves of the crank-shaft bearing constantly in contact with the same. In stopping or starting the engine, the steam-pressure upon the pistons at such time being absent, there would be nothing to prevent pounding in the absence of said spring, and the latter are therefore employed to hold the parts of the crank-pin bearings always in contact with said crank-pin.

The features of construction above described are especially valuable and useful for high-speed engines.

One advantage arising from the construction herein described is that the cylinder-ports are very short and afford direct communication between the steam-chamber of the valve and the cylinder. The novel construction in the valve herein described is especially valuable in a compound engine, because the construction in the steam-distributing devices permits the whole of such devices to be included in a space between the covers of the high and low pressure cylinders, thereby affording short and direct passages for the steam in passing from one of said cylinders to the other and involving little diminution of pressure and little or no loss of heat from radiation. Furthermore, this construction and location of the distributing devices afford a jacket for the cylinder ends, preventing the loss of heat from the same. The intercepting valve S operates to reduce to a minimum the period during which the walls of the low-pressure cylinder are exposed to the cooling effect of the condenser or exhaust. A single-acting compound engine having the divided crank-shaft bearing and independent devices for transmitting power from the two pistons to the crank-shaft has the advantage of the single-acting type of "box engine"—to wit, compactness, smoothness of working, self-lubrication, and of requiring little attention. The engine herein described, however, having no open-ended cylinder in direct communication with the

"box-room," the lubricant is not spoiled by the water of condensation, which always finds its way past the packings of the pistons in this class of engines as usually constructed.

I claim as my invention—

1. The combination, with an engine-cylinder having live-steam and exhaust chambers and provided with an annular valve-seat having a plurality of ports therein and an annular bearing-surface opposed to said valve-seat, of a movable valve-ring bearing at its opposite faces against said valve-seat and bearing-surface and separating the said live-steam and exhaust chambers, said valve-ring being provided with two sets of recesses or notches opening, respectively, at the inner and outer cylindrical surfaces of said valve-ring and both communicating with its bearing-surface, which is in contact with said valve-seat, substantially as described. 75

2. The combination, with an engine-cylinder having live-steam and exhaust chambers and provided with an annular valve-seat having a plurality of ports therein and an annular bearing-surface opposed to said valve-seat, of a movable valve-ring bearing at its opposite faces against said valve-seat and bearing-surface and separating the said live-steam and exhaust chambers, said valve-ring being provided with two sets of recesses or notches, opening, respectively, at the inner and outer cylindrical surfaces of said valve-ring and both communicating with its bearing-surface, which is in contact with said valve-seat, said valve-ring embracing a packing-ring bearing against said annular bearing-surface and having sliding engagement with the valve-ring, substantially as described. 90

3. The combination, with an engine-cylinder having live-steam and exhaust chambers and provided with an annular valve-seat having a plurality of ports therein and an annular bearing-surface opposed to said valve-seat, of a movable valve-ring bearing at its opposite faces against said valve-seat and bearing-surface and separating the said live-steam and exhaust chambers, said valve-ring being provided with two sets of recesses or notches opening, respectively, at the inner and outer cylindrical surfaces of said valve-ring and both communicating with its bearing-surface, which is in contact with said valve-seat, said valve-ring embracing a packing-ring bearing against said annular bearing-surface and having sliding engagement with the valve-ring, and springs applied to hold said packing-ring in contact with said annular bearing-surface, substantially as described. 105

4. The combination, with the high and low pressure cylinders of a steam-engine, of an annular exhaust-port at one end of the low-pressure cylinder, and located in a position to be uncovered by said piston at one end of its stroke, and an auxiliary valve controlling the exhaust-passage from said cylinder, substantially as described. 110

5. The combination, with the high and low

pressure cylinders of a compound engine arranged end to end and having on their adjacent ends annular valve-seats having a plurality of ports, of exhaust and live steam chambers and valve-rings upon said seats separating said chambers and provided with two sets of notches opening at opposite sides of the rings, substantially as described.

6. The combination, with the high and low pressure cylinders of a compound engine arranged end to end and having on their adjacent ends annular valve-seats having a plurality of ports, of exhaust and live steam chambers, valve-rings upon said seats, provided with two sets of notches opening at opposite sides of the rings, and a cut-off valve consisting of an apertured movable cylinder located between the valve-ring which controls the high-pressure cylinder and the live-steam chamber, substantially as described.

7. An engine-cylinder provided at one end with steam-inlet ports and exit-ports and a valve controlling the same, and with an annular exhaust-port at the opposite end of the cylinder, combined with a piston in said cylinder, said annular exhaust-port being located in position to be uncovered by the piston at the end of the stroke of the latter, substantially as described.

8. The combination, with the high and low pressure cylinders of a compound engine arranged end to end and having at their adjacent ends annular valve-seats having a plurality of ports, of exhaust and live steam chambers or passages, valve-rings upon said seats, each provided with two sets of notches opening at opposite sides of the rings, the

high-pressure cylinder being provided at its opposite or outer end with an annular exhaust-port communicating with the steam-space between said valve-rings, and said low-pressure cylinder being provided with a similar annular port communicating with the exhaust chamber or passage, substantially as described.

9. The combination, with two single-acting cylinders arranged end to end, of pistons in said cylinders and piston-rods, one of which is tubular for the passage of the other, a crank-shaft, a divided crank-pin bearing, the parts of which are separately connected with said pistons, and a spring or springs applied to hold the parts of the bearings in contact with the crank-pin, substantially as described.

10. The combination, with two single-acting cylinders arranged end to end, of pistons in said cylinders, piston-rods, one of which is tubular for the passage of the other, a two-part cross-head, the parts of which are separately attached to the piston-rods, a crank-shaft, a divided crank-pin bearing, the parts of which are separately connected with the parts of the divided cross-head, and a spring or springs applied to the parts of the divided cross-head to hold the parts of the crank-pin bearing in contact with the crank-pin, substantially as described.

In testimony that I claim the foregoing as my invention I affix my signature in presence of two witnesses.

CHARLES BROWN.
